UNITED STATES PATENT OFFICE.

CHARLES ALLEN, OF EL PASO, TEXAS.

SLIME-PULP THICKENER.

Application filed June 9, 1917. Serial No. 173,785.

To all whom it may concern:

Be it known that I, CHARLES ALLEN, a citizen of the United States, residing at El Paso, in the county of El Paso and State of Texas, have invented new and useful Improvements in Slime-Pulp Thickeners, of which the following is a specification.

This invention relates to the thickening of slime or pulp.

10 Thickening, which is a partial dewatering of finely divided solids in suspension, is almost universally used in the treatment of ores by wet milling processes, and in its every application it is of prime importance, 15 that the degree of thickening be uniform, that is, that the discharge of the thickened slime be always of the same density. Thickeners heretofore used depend upon the volume of pulp fed to the cone or tank for regulation of the size of the discharge orifice. 20 The results are very unsatisfactory, inasmuch as the proportions of liquids to solids in the material discharged varies with the volume of slime pulp fed to the thickener.

25 In the present invention, the volume of slime pulp in the thickener in no manner alters the proportion of liquids to solids in the products discharged, within the limits of the capacity of the machine. The degree 30 of thickening is controlled by the increase in specific gravity due to the settling of the material of heavier specific gravity without reference to the volume fed to the thickener, and for whatever degree of thickening the 35 device is adjusted, that degree of thickening is automatically maintained.

In slime pulp, the finely divided solids move freely without appreciably affecting the fluidity by friction among themselves. 40 Such a pulp has the properties of a liquid so long as the solids are kept in suspension. When the pulp is composed of water and solid particles of greater specific gravity than water, the specific gravity of the pulp increases with all increases in the quantity of solids in suspension in the pulp. This 45 pulp may therefore be considered as a liquid of greater density than water.

50 In my invention I employ two connected compartments having in one compartment a liquid and in the other a mixture of liquids and solids or pulp. The variations in the density of the pulp, due to the presence of more or less solids in suspension, act to 55 raise and lower the column of liquid, which

column of liquid carries a float operatively connected to a valve at the bottom of the tank controlling the discharge orifice. When the pulp attains a certain density, the valve is automatically opened to permit the discharge of the thickened pulp through the bottom orifice, and when the density of the pulp falls below a critical point, the valve is automatically operated to close the orifice. Hence the degree of thickening of the pulp 60 discharged through the automatically controlled orifice is practically the same under all conditions or variations in the volume of slime pulp fed into the tank. The volume of thickened slime discharged through the 65 orifice may vary considerably, but the density of the thickened slime discharged remains practically constant. This is the reverse of the thickeners ordinarily used in which the volume of thickened slime discharged remains constant while the density 70 of the discharge varies with the quantity fed into the thickener.

A form which my invention may assume is exemplified in the following description 80 and illustrated in the accompanying drawing, in which—

The figure is a view in central, vertical section disclosing an embodiment of my invention, and particularly illustrating the 85 position and operation of the final elements thereof.

As here shown the apparatus comprises a tank 10 in the shape of an inverted cone having a discharge orifice 11 at its bottom for carrying off the thickened product. A launder 12 is arranged at the top of the tank for carrying off clear liquid which overflows and a conduit 13 supplies slime pulp to the tank. A float 14, having its buoyancy variable by adjustable weights 15, has operative connections 16 with a valve 17 which controls the discharge orifice, and a chamber 18 is provided for the float, said chamber extending to a higher level than the normal level of pulp in the tank and being adapted to contain clear water, preferably supplied through a pipe 19. This chamber, 90 is one of two connected compartments a U-shaped conduit of which the tank with its 95 pulp forms the other, the two being so arranged that a hydrostatic balance is maintained between the column of water on the one hand and the pulp on the other. The 100 variations in the density of the pulp outside 105

the float chamber act to vary the height of the column of water within and thereby to raise or lower the float and through it open or close the discharge valve.

- 5 In the form of the invention shown in the drawing, the float 14 and its chamber 18 are positioned centrally within the tank 10 and the float chamber is in the form of a cylinder open at its ends and having its lower 10 end projecting some distance downwardly within the tank.

To prepare for the thickening operation, the cone 10 and the cylinder 18 are filled with clear water until the water overflows 15 into the launders. The weights 15 are adjusted so as to give the float 14 the proper buoyancy to insure opening of the valve 17 when the pulp reaches the desired degree of thickening in the cone. The slime pulp to 20 be thickened enters the cone through conduits 13 and the thickening begins at once, the solid particles settling toward the bottom of the cone and the clear water rising therein and overflowing into the launder 12. At 25 the first stage there is no discharge of thickened pulp through the discharge orifice 11, but gradually, as the thickened slime fills the tank, the density of the same above the bottom of the cylinder 18 increases and acts 30 upon the column of water inside of the cylinder to raise the same around the float 14. The float will not rise until the pulp in the tank has reached the degree of thickening for which the buoyancy of the float was previously set by the weights 15. When the 35 float line is reached, the float rises and through the connections 16 lifts the valve 17 from its seat, thus permitting the discharge of the thickened slime in volume proportionate to the extent of movement of the float. The discharge is wholly controlled by the 40 density of the contents of the tank above the bottom edge of the chamber 18.

If the outlet is opened too far and discharges the thickened slime faster than it is settling and thickening in the tank to the required degree, the density of the contents is lowered, and, inasmuch as a hydrostatic balance is at all times necessary between the 45 column of water in the chamber 18 and the material in the tank above the bottom of said chamber, the water level in the chamber 18 will be lowered, thus lowering the float 14 and closing or partially closing the valve. Should the slime be thickened in the 50 tank faster than it is being discharged, the density of the contents thereof acting upon the column of water in the chamber 18, will cause a further rise of the water carrying 55 with it the float and thereby further opening the valve to the required extent. The water in the chamber 18 being practically stationary and without agitation, its only movement being a slow vertical rise and fall with no overflow, it remains compara-

tively clear and free from solids in suspension and thus the effect of the solids in suspension in the material outside of and surrounding the chamber 18 is preserved for actuating purposes.

It will thus be seen that I make use of a hydrostatic balance between two liquids of different density to automatically control the discharge of the thickened product. Among the advantages of this system may be mentioned: First, that until the thickening has progressed to a certain definite density the orifice through which the thickened product is discharged remains closed, but as soon as the thickening has reached the desired point, 70 the orifice is automatically opened. Second, if while the thickened product is being discharged, the degree of thickening falls below the required consistency, the discharge valve is automatically closed. Third, if the thickened product while being discharged increases or decreases in consistency beyond what is desired, the discharge valve is automatically moved to partial opening or closing position in order to restore the discharged product to the required consistency. Fourth, the relative proportion of solids to 80 water in the thickened product discharged is under perfect control by simply altering the float line of the actuating float, and for whatever proportion of water to solids the float is weighted, that proportion is automatically maintained. This means that the density of the thickened product discharged remains practically the same under all working conditions. At the commencement of operations 10 and 18 are full of water (density 1.00) to the overflow lip of 10. The slime to be thickened is now fed into 10 from 85 13, we will assume its density to be 1.07 and that it is to be thickened in 10 above the bottom edge of 18 until its density is 1.20. As the thickening proceeds in 10 to maintain 90 hydrostatic equilibrium between the liquid column of greater density in 10 and the liquid column of lesser density in 18; the surface of the liquid in 18 must rise above the level of the surface of the thickened material in 10 a distance directly proportional to the 95 difference in density between the two columns.

Assume the vertical height of the liquid column in 10 from its surface to the bottom edge of 18 to be 50 inches, under the above 100 stated conditions when the column in 10 has attained a density of 1.20 the surface of the column in 18 (density 1.00) will be 10 inches above the surface of the balancing column in 10, (density 1.20).

Assume the actuating float 14 to be so suspended in 18 that it is not buoyant until the 105 surface of the liquid in 18 has risen 10 inches above the surface of the liquid in 10 and that the float then becomes buoyant. It is evident that the spigot 11 will remain closed 110

by the valve 17 until the float becomes buoyant, and in this case that is until the balancing column of liquid in 10 has attained a density of 1.20. Any further increase in the density of the column in 10 causes a corresponding rise of the liquid in 18 and with it rises the now buoyant float 14, which through the connections 16 removes the valve 17 from the spigot 11 through which outflows the thickened material in 10 in quantity proportionate to the area of the spigot opening, which is proportionate to the rise of the float 14, which rise is in direct proportion to the density of the liquid column in 10, which causes the further opening of the spigot orifice when its density increases, and its closure when the density of the column in 10 falls below 1.20. A thickener so built gives a definite degree of thickening. It will be understood, of course, that the actuating float may be so built as to give a definite degree of thickening without varying the buoyancy thereof and hence the adjustable weights 15 may be omitted for a certain class of thickening, but means whereby the float line of the actuating float may be altered must be used in order to be able to adjust the thickener to various degrees of thickening.

Various changes in the construction and arrangement of the several parts herein shown and described may be employed without departing from the spirit of my invention as disclosed in the appended claims.

It is understood wherever the word "water" is used that I include in that term any other liquid or solution employed in practical mining operations and with pulp to be subjected to my process.

Having thus described my invention, what I claim and desire to secure by Letters Patent is:

1. A thickener for slime pulp comprising a vessel having a bottom discharge orifice for quickly settling and heavy particles and a rim overflow for slowly settling and light particles, a valve to control said bottom discharge orifice, a float column in operative communication with that portion of the vessel where the said material accumulates, means for admitting fluid of fixed density into said column, and a float in said column operatively connected with the valve in the bottom discharge orifice, whereby an increase in density of such accumulated material—due to settling—will act to raise the column of fluid of fixed density and with it the float for the purpose of opening the valve

to permit such accumulated material to be discharged.

2. A thickener as set forth in claim 1 having means to vary the float line of the float to cause variation in the density of the discharged product.

3. A thickener for solids suspended in liquid, and which suspension varies in density from time to time, comprising a settling vessel having a bottom orifice for the discharge of quickly settling and heavy particle and open at its top to permit the slowly settling and light particles to overflow the rim, a valve to control the bottom discharge orifice, a float column having an outlet opening into said vessel, a float in said column operatively connected to the valve, means for supplying fluid of a fixed density to the float column, and means opening into the vessel exterior of the float column for supplying material to be treated thereto, whereby when the settled material in the vessel has acquired a sufficient density to obstruct the outlet on the float column the latter becomes filled with fluid of a fixed density and causes the float to rise thereby opening the valve.

4. A thickener for solids suspended in liquid, and which suspension varies from time to time, comprising a conical settling tank having its apex at the bottom and formed with an orifice for the discharge of heavy and quickly settling particles and being open at its top to permit light and slowly settling particles to overflow its rim, a valve to control the bottom discharge orifice, a float chamber extending from a point above the top of the tank down into the interior thereof and open at its lower end, a float in said chamber operatively connected with the valve, means for continuously supplying clear water to the float chamber, and means opening into the tank outside the float chamber for supplying material to be treated, whereby when the settled material in the tank has acquired a sufficient density to obstruct the bottom of the float chamber the latter will become filled with fluid of a fixed density, thereby lifting the float and causing the valve to be opened.

In testimony whereof I have hereunto set my hand in the presence of two subscribing witnesses.

CHARLES ALLEN.
